Jacob S. Nettling. Gloucester & Maine

Letters Patent

The Schedule referred to in these Letters Patent and making part of the same containing a description in the words of the said Jacob S. Nettling himself of his improvement in the machine for threshing Wheat and other Grains.

To all people to whom these presents shall come. Be it known that I Jacob S. Nettling of New Gloucester in the County of Cumberland & State of Maine have invented a new and useful improvement in a machine for threshing Wheat and other grains and that the following is a full and exact description thereof.

I make a frame thirty six inches long and twenty four or twenty six inches high with four pieces as in letter A ~~of the spec~~ on the top of which is a ^{horizontal} ~~vertical~~ post on by means of a mortise & tenon as in letter B ~~of the spec~~. Then I band it on the inside with plank or shingle boards and let the posts into the bands and cover them over as in letter C. ~~of the spec~~. This is fastened together by means of iron rods, wholly with nuts and screws as in letter D. ~~of the spec~~. one end also is bandied up and on the inside and is projecting pieces on which the said Table rests as letter E ~~of the spec~~. Then I make a top or cover to go over the beater wheel with sufficient length and breath to cover the wheel and to prevent things in and about from flying too far as in letter F. ~~of the spec~~. Through the top of which I convey the wind from the beater wheel by means of a blunt or circular band or sheet iron. This band or sheet iron goes through the top or cover and meets the teeth of the beater wheel in right form as to receive the wind from the wheel and convey it back from the top as in letter G. ~~of the spec~~. in the front end I have a cover or frame from the table to the beater wheel as in letter H. ~~of the spec~~. The ~~or~~ cover is fastened to the frame by means of four plates to each

June 2, 1836

let into the girls or beams, as in letter A. Next appear. The beater wheel is made of Oak wood. I take four pieces of bar iron four inches wide and one inch thick and as long as I want the beater wheel in diameter, put them across at right angles and then split each end of each bar iron with three inches of the centre, and spread them till they come at right distances apart, then ~~protrude~~ ^{protrude} each piece with a turn not one inch square and so construct them as to fit the lags and not to come in the way of the teeth in the beater wheel lags as letter J. Next appear. when these pieces are split with compass eight arms as letter H. Next appear. Then I take eight pieces of bar iron three inches wide and one inch thick, and as long as I want the beater wheel, and make a mortise, so much round and so fit them as to receive the before described arms and crosswise the mortise and rivet. the tenons as in letter L. Next appear. Then I take seven pieces of bar iron for the concave. three inches wide and three fourths of an inch thick and place them on the before described pieces of plane by means of a groove in a circular form as in letter M. Next appear. I make the teeth of cast one inch and a half wide at the top and three fourths of an inch thick and three inches long and taper of each way to one inch wide and one fourth of an inch thick at the top and as in letter N. Next appear. These teeth are made with two tenons one on each end of the teeth about two fourths of an inch through wood so as to fit into the lags and concave pieces by placing them on and driving them cold and counterboring the ends and riveting them when cold as in letter P. Next appear. These last are to set in the lags and concave pieces as to pass by each other & not to hit each other. Then I take a square bar of iron for a shaft one inch and one half square and put it through the before described arms and fasten it on by means of bolts or keys as letter Q. Next appear. This shaft is turned and fitted to run on cast iron bars these bars are bolted down to the before described beams or girts. one end of the shaft is a pulley about eight inches in diameter as in letter R. Next appear: on the end pulley goes a band from a hole

the power which sets the machine in motion. Underneath the beater
is fixed a blow or fly wheel of sufficient size and is constructed
by means of a band from the beater wheel pulley to the blow or fly wheel
which forces the wind out at the end of the machine and separates
the straw and chaff from the wheat as in other S. doth appear.

What I claim as my own invention and previously known is the
above described machine is first. The way and manner of making
the beater wheel and its being made wholly of cast iron and the
way and manner and form of making and setting the teeth with
the levers (and also the invention of the wind through the top of
the machine) also the blow or fly wheel underneath the beater wheel.
